UNITED STATES PATENT OFFICE.

HENRY L. PERRYMAN, OF SPRINGFIELD, OHIO, ASSIGNOR, BY DIRECT AND MESNE ASSIGNMENTS, TO THE NATIONAL TONGUELESS BUCKLE COMPANY, OF SPRINGFIELD, OHIO, A CORPORATION OF OHIO.

BELT-BUCKLE.

No. 909,213.

Specification of Letters Patent.

Patented Jan. 12, 1909.

Application filed January 17, 1908. Serial No. 411,244.

To all whom it may concern:

Be it known that I, HENRY L. PERRYMAN, a citizen of the United States, residing at Springfield, in the county of Clark and State of Ohio, have invented certain new and useful Improvements in Belt-Buckles, of which the following is a specification, reference being had therein to the accompanying drawings.

10 This invention relates to belt buckles, and the object of the invention is to provide a buckle of this character whereby the free end of the belt will be engaged and disengaged at any desired point without per-
15 forating or in any way marring the belt, and, when so engaged, will be firmly se-
cured in position; and further, to provide such a buckle which will be of a neat ap-
pearance and will be inexpensive to manu-
20 facture.

With these objects in view my invention consists in certain novel features of construction and in certain parts and combina-
25 tions hereinafter to be described, and then more particularly pointed out in the claims.

In the accompanying drawings, Figure 1 is a perspective view of a belt provided with a buckle embodying my invention; Fig. 2 is a longitudinal sectional view of the buckle;
30 Fig. 3 is a detail perspective view of the tongue; Fig. 4 is a rear face view of the frame of the buckle; Fig. 5 is a longitudinal, sectional view of a buckle having a slightly modified form of frame; Fig. 6 is
35 a side elevation of a modified form of the buckle; Fig. 7 is an edge view of such a buckle; Fig. 8 is a front view of the body portion or frame of the same buckle; and Fig. 9 is a sectional view on the line α α of Fig. 8.

In Figs. 1 to 4 I have shown one form of my invention, and, as here shown, the buckle comprises a body portion or elongated frame 1 having ears or lugs 2 depending from the opposite sides thereof near the longitudinal center of the frame. The interior of the body portion is preferably cut away and the side members of the frame are connected by a transverse bar 3 which preferably has its inner face concave, as shown at 4. A suitable tongue having a resilient clamp-
45 ing member is pivotally connected at one end to the body portion 1 of the buckle and has its other end adapted to be connected

55 to the belt 5 and is provided with a resili-
ent clamping member adapted to clamp the belt against the frame or body portion of the buckle, which forms a support therefor, and secure the same firmly in its adjusted position. In the form here shown, this 60 tongue comprises a member or plate 6 pro-
vided at its inner end with pivot lugs 7 adapted to engage the apertured ears or lugs 2 on the body portion of the buckle. The outer end of the plate 6 is provided 65 with suitable means for securing the same to the belt, such as a transverse slot 8 adapt-
ed to receive clips 9 which are secured to the end of said belt.

The clamping member consists of a plate 70 10 of resilient material rigidly secured at one end to the plate 6 at a point removed from the pivotal center thereof and having its other end extending gradually away from the plate 6 to a point near said pivotal cen-
75 ter and thence more abruptly away from said plate to form a projection 11. The inner ends of the plate 6 and the resilient member 10 are spaced some distance apart to permit free play of the resilient member. 80 Thus, it will be seen that when the tongue is in a position substantially at right angles to the body portion of the buckle, the belt can be readily inserted between the clamp-
85 ing member and the body portion of the buckle, and that when said tongue is moved to a position substantially parallel with the body portion of the buckle, the projection 11 of the resilient clamping member will en-
90 gage the belt and clamp the same against the transverse bar 3 of the frame or body portion of the buckle, the concave inner face of this bar affording a better gripping sur-
95 face than a plane face and enabling the belt to be clamped securely in position. The re-
silience of the clamping member enables the same to be clamped tightly upon the belt without marring or defacing the same and provides a clamping member which will exert a uniform pressure upon the belt at 100 all times and will not become loose and in-
operative through the wearing away or springing of the metal comprising the same.

In Fig. 5 I have shown a form of buckle in which the transverse bar 3 of the body portion is provided with a raised central portion, as shown at 12, the projection 11 of the resilient clamping member 10 engaging

the bar 3 at one side of the rib 12 and thus clamping the belt about said projection.

In Figs. 6 to 9, I have illustrated another form of buckle comprising a body portion or frame 13 of relatively thin metal having formed therein a slot 14 extending transversely of the belt. The body portion 13 is provided near each end of the slot 14 with inwardly extending apertured lugs 15 which are preferably formed by bending inwardly a portion of the metal removed to form the slot 14. In this form of buckle, the tongue, which is preferably formed of a single piece of metal bent upon itself to form a substantially U-shaped member, comprises a body portion or member 16, provided with pintles 17 adapted to engage the apertured lugs 15 of the frame or body portion 13 and having a clamping portion, such as the resilient plate 18, diverging therefrom and having its inner end turned at an angle thereto, as shown at 19, to provide a projection adapted to engage the belt. The members 16 and 18 of the tongue are preferably of substantially the same length, whereby the projection 19 lies in substantially the same plane as does the pivotal center of said tongue. The two members of the tongue are here shown as extending parallel for a portion of their length and thence diverging toward their inner ends. The outer end of the tongue is preferably provided with a transverse slot 20 adapted to receive the end of the belt 21. Inasmuch as the belt and the tongue are substantially the same width, I prefer to provide that portion of the belt 21, which passes through the slot 20, with a longitudinal slot 22 between the edges thereof, thus permitting the sides of the belt to be compressed to reduce the width thereof at the point where it engages the slotted end of the tongue. The operation of this form of the device is substantially the same as that of the first form described, but the form here shown is lighter in weight, neater in appearance and much cheaper to manufacture as the parts thereof can be struck from sheet metal.

From the foregoing description, it will be seen that I have provided a belt buckle which, when secured to one end of the belt, may be engaged with and disengaged from the free end thereof without puncturing the same or in any way marring or defacing the surface thereof, and that, when in engagement with the belt, will be held firmly in its adjusted position thereon, any pull on the belt serving to tighten the grip of the eccentrically arranged resilient clamping member thereon; and further, that I have provided a buckle which is very neat in appearance, light and durable, and which may be manufactured at a low cost.

It will be apparent that the device is subject to modification and that either form of

tongue herein shown may be used with either form of the frame or body portion of the buckle, and I wish it to be understood that I do not desire to be limited, except as required by the scope of the appended claims, to the exact details of construction shown and described, for obvious modifications will occur to a person skilled in the art.

Having thus fully described my invention, what I claim as new and desire to secure by Letters Patent, is:—

1. In a belt buckle, the combination, with a frame or body portion, of a tongue having one end pivotally connected to said frame, adapted to have its other end connected to one end of a belt and having a resilient clamping member adapted to secure the other end of said belt to said frame.

2. In a belt buckle, the combination, with a frame or body portion, of a tongue comprising a member having one end pivotally connected to said frame and adapted to have its other end connected to one end of a belt, a resilient plate connected to said member at a point removed from the pivotal center thereof and diverging therefrom, and a projection carried by the free end of said plate and adapted to clamp the belt against said frame.

3. In a belt buckle, the combination, with a frame or body portion, of a tongue comprising a member having one end pivotally connected to said frame and adapted to have its other end connected to one end of a belt, a resilient plate extending longitudinally of said member and having one end connected thereto at a point removed from the pivotal center thereof and its other end diverging from said member toward said pivotal center, and a projection carried by said plate and adapted to clamp said belt against said frame.

4. In a belt buckle, the combination, with a frame or body portion, of a tongue comprising a plate of resilient material bent upon itself and adapted to be connected to one end of a belt and having its ends separated one from the other, one of said ends being pivotally connected to said frame and the other of said ends having a projection adapted to clamp said belt against said frame.

5. In a belt buckle, the combination, with a frame or body portion comprising a plate having a slot therein, and lugs extending inwardly at the ends of said slot, of a tongue pivotally mounted on said lugs, adapted to have the belt connected to the outer end thereof and having a resilient member adapted to engage said belt between said lugs.

6. In a device of the character described, the combination, with a belt, a buckle comprising a frame or body portion, and lugs extending inwardly therefrom at points removed from the ends thereof, of a plate,

substantially equal in width to the width of said belt, pivotally mounted on said lugs and having a transverse slot near the outer end thereof adapted to receive said belt, that 5 portion of said belt which passes through the slot in said plate having a longitudinal slot between the sides thereof, and a resilient clamping member carried by said belt and

adapted to clamp said belt against said frame.

In testimony whereof, I affix my signature in presence of two witnesses.

HENRY L. PERRYMAN.
